UNITED STATES PATENT OFFICE.

GEORGE CALTIS, OF MEMPHIS, TENNESSEE.

DESIGN FOR A BOTTLE.

Application filed July 30, 1924. Serial No. 10,318. Term of patent 14 years.

To all whom it may concern:

Be it known that I, GEORGE CALTIS, a citizen of the United States, residing at Memphis, in the county of Shelby, State of Tennessee, post-office address 645 Marshall Avenue, Memphis, Tennessee, have invented a new, original, and ornamental Design for Bottles, of which the following is a specification, reference being had to the accompanying drawing, forming part hereof.

The figure is a perspective view of a bottle showing my new design.

I claim:

The ornamental design for a bottle as shown.

GEORGE CALTIS.
